CLAIM

The ornamental design for a single bag with an inner portion of a first pigment, and an outer portion of a second pigment and a pattern, as shown and described.

DESCRIPTION

FIG. 1 is a front perspective view of a single bag that includes a white inner portion of which only the dotted box region is claimed, and a pigmented outer portion with pattern;

FIG. 2 is a front elevational view of the single bag of FIG. 1, the back view being a mirror image thereof;

FIG. 3 is an inside-out view of the single bag of FIGS. 1 and 2 showing the white inner portion of the single bag of which only the dotted box region of the white inner portion is claimed;

FIG. 4 is a close-up view of part of the pigmented outer portion with pattern designated by dotted box 4 of FIG. 1; FIG. 5 is a cross-sectional view, taken along line 5-5, of the portion shown in FIG. 4; and, FIG. 6 discloses the outer bag portion shown in FIG. 4 in a stretched configuration.

The broken lines in the drawings illustrate portions of the single bag that form no part of the claimed design. In particular, in the Figures, only the bag outlines and those portions of the single bag enclosed within the phantom outlined boxes are claimed. Moreover, no particular colors are claimed and, as such, the white inner portion and stippled outer portion are presented only by way of example. The bracket showing broken away portions in FIGS. 1-3 illustrate the bag has no specific length.
